R. A. IRBY

TOY GUN

Filed Nov. 28, 1924

UNITED STATES PATENT OFFICE.

RUFUS A. IRBY, OF LONG BEACH, MISSISSIPPI.

TOY GUN.

Application filed November 28, 1924. Serial No. 752,714.

To all whom it may concern:

Be it known that I, RUFUS A. IRBY, a citizen of the United States, residing at Long Beach, in the county of Harrison and 5 State of Mississippi, have invented certain new and useful Improvements in Toy Guns; and I do hereby declare the following to be a full, clear, and exact description of the invention, such as will enable others skilled 10 in the art to which it appertains to make and use the same.

The present invention provides a toy for projecting missiles such as pins, shots and the like, and which embodies an action similar to a rifle since provision is had for an explosion and a hammer and trigger action, the hammer being thrown forward by a main spring and held in retracted position by means of a lock which is released by a 20 trigger when the gun is fired.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to 30 without departing from the nature of the invention.

Referring to the accompanying drawings forming a part of the specification,

Figure 1 is a side view of a toy gun embodying the invention,

Figure 2 is an enlarged detail sectional view,

Figure 3 is a detail view of a portion of the gun as seen from the lower side,

Figure 4 is a sectional view on the line 4-4 of Figure 2,

Figure 5 is a sectional view on the line 5-5 of Figure 2, and

Figure 6 is a detail sectional view on the line 6-6 of Figure 2 looking in the direction of the arrows.

Corresponding and like parts are referred to in the following description and designated in the several views of the drawings 50 by like reference characters.

The numeral 10 denotes the barrel of the gun and 11 the stock to which the barrel is attached, said stock in the preferable construction comprising similar side pieces disposed in parallel relation and spaced apart

to receive the barrel, the lock mechanism and a magazine 12, which may receive paper caps or the missiles to be fired, said magazine having an opening in its front which is normally closed by means of a cover 13 which is preferably pivoted. The magazine 12 is secured between the front portion of the side pieces comprising the stock, and provides a rest for the barrel 10, the latter being fitted in grooves or channels 14 formed in the opposing faces of the guide pieces projecting above the magazine 12 as indicated most clearly in Figure 5.

A plunger 15 is loosely fitted within the breech of the barrel 10 and is held in place 70 by means of a pin 16 which passes through a longitudinal slot 17 of the plunger and through openings in the side pieces comprising the stock to assist materially in securing the same. The rear portion of the 75 plunger 15 is recessed as indicated at 18 and grooved to receive a paper cap which is exploded when the gun is fired, thereby simulating the action of a rifle and at the same time materially assisting in the propulsion of the missile. A spring 19 is secured at one end between the side pieces comprising the stock and its free end is provided with a hammer 20 which is adapted to explode the paper cap and project the 80 plunger 15 when the gun is fired to project a missile 21 which may consist of a pin or other projectile. A dog 22 carried by the spring 19 is adapted to engage a stop 23 when the gun is cocked by drawing the 90 hammer back into firing position as indicated by the full lines in Figure 2. The trigger comprises a post 24 a guard 25 and a lug 26, the latter being pivoted to the stock and the post 24 slotted to receive the 95 main spring 19 as shown most clearly in Figure 4. The projecting end of the spring 19 is notched as indicated at 27 to provide a rear sight which is adapted to cooperate with a corresponding sight at the muzzle 100 of the barrel. It is observed that the action or lock mechanism is comprised between the side pieces forming the stock and as a result the parts are readily accessible, and the construction is simple and admits of 105 ready assembling of the parts and an expensive production which is essential in an article of the nature of the present invention.

What is claimed is:—

1. A toy gun comprising a barrel, a plunger loosely fitted within the breech of the barrel and having its rear portion recessed for the reception of a paper cap, and an action comprising the hammer, spring and lock and trigger mechanism. and a trigger mechanism for releasing the dog, said trigger mechanism comprising a post slotted for the passage of the said spring therethrough and a guard carrying the trigger post and pivoted to the stock.
2. A toy gun comprising a stock, a magazine disposed at the front portion of the stock, a barrel fitted to the stock and supported upon the magazine, a plunger within the breech of the barrel and having its rear portion recessed to receive a paper cap, and an action comprising a hammer, spring and lock and trigger mechanism. 5. A toy gun comprising a stock formed of similar side pieces disposed in parallel and spaced relation, a barrel held between said side pieces, a plunger within the breech of the barrel and having its rear portion recessed to receive a paper cap, and an action comprising a spring, hammer, dog, stop and trigger mechanism comprised between the side pieces forming the stock.
3. A toy gun comprising a stock, a barrel thereon, a plunger within the breech of the barrel and having its rear portion recessed to receive a paper cap, a spring provided with a hammer for operating the plunger, a dog carried by the spring, a stop adapted to coact with the dog to hold the spring when set for action, and a trigger mechanism for releasing the dog. 6. A toy gun comprising a stock formed of similar side pieces disposed in spaced and parallel relation, a magazine arranged between the front portion of the side pieces, a barrel supported upon the magazine and clamped between the side pieces of the stock, a plunger in the breech of the barrel and recessed to receive a paper cap, a spring provided with a hammer to coact with the plunger, a dog carried by the spring, a stop adapted to engage the dog and a trigger mechanism, the action being comprised between the side pieces forming the stock.
4. A toy gun comprising a stock, a barrel thereon, a plunger within the breech of the barrel, a spring provided with a hammer for operating the plunger, a dog carried by the spring, a stop adapted to coact with the dog to hold the spring when set for action, In testimony whereof I affix my signature.

RUFUS A. IRBY.
